MICROWAVE ROTATABLE JOINT

John F. Zaleski, Valhalla, N. Y., assignor to General Precision Laboratory Incorporated, a corporation of New York

Application September 20, 1951, Serial No. 247,519

10 Claims. (Cl. 333—33)

1

This invention pertains to microwave hollow guide rotatable joints and more specifically to rotatable joints which provide angularly variable connections between hollow guides of rectangular or circular cross-section.

In interposing a rotating joint in rectangular guide some device is obviously necessary to control the effective microwave polarization in the joint so that at each rectangular terminal the microwave polarization is exactly the same as the terminal orientation. In other words, the microwave energy as it passes through the device must be changed in field polarization by exactly the same amount as the device rotates in its physical orientation.

In interposing a rotating joint in round guide any ordinary type of joint can be used if the guide carries a circularly symmetrical mode, but if the guide carries the dominant or $TE_{1,1}$ mode, or any other non-symmetrical mode, a joint that forces the field to rotate as the joint is rotated is essential. This action occurs in the joint of the present invention.

The joint of the present invention is completely mobile; that is, it can be rotated for any number of degrees at any speed which is mechanically feasible. The joint can be employed for the mobile coupling of two rectangular guides, two round guides, or of a rectangular guide to a round guide.

The invention provides two similar guide transitions connected by a rotary joint. Each transition is of the type used for the axial connection of a coaxial transmission line with a rectangular or round hollow guide, and each transition includes a hollow guide side arm stub and an antenna positioned within the hollow guide. The hollow guide side arm stub is preferably, for convenience, of the rectangular type, whether connected to a rectangular or round guide termination. The two transitions are connected by their coaxial members, which therefore form a substantially single common member, and which contains at a mid-position some modified type of coaxial rotary joint. Each half of the device is a complete transition from coaxial conductor to rectangular or round guide, and has utility in and of itself as a sub-combination which can be used elsewhere than in a complete rotatable joint.

The general purpose of this invention is to provide a compact and efficient motionless joint in hollow waveguide which is easy to design and construct for use at any microwave length.

A specific purpose is to provide a mobile joint

2

for two rectangular guides which are axially aligned.

Another purpose is to provide a compact rotary joint for rectangular guide or round guide when operated in a non-circular mode.

A further purpose is to provide an improved end-to-end transition between a rectangular hollow guide and coaxial microwave conductors.

10 A further understanding of the invention may be secured from the detailed description and the accompanying drawings in which:

Fig. 1 is an oblique view of one embodiment of the microwave guide rotatable joint of the invention.

15 Fig. 2 is a sectional view taken on the line 2—2 of Fig. 1.

Fig. 3 is a sectional view taken on the line 3—3 of Fig. 1.

20 Fig. 4 is a schematic view illustrating the operation of the device.

Referring now to Fig. 1, a rectangular guide 11 is secured and electrically connected to one end of the device of the invention by means of a conventional choke flange 12 fastened to a plain flange 13.

25 The two flanges 12 and 13 are fastened together by means of four screws of which two are visible at 14 and 16. Such a choke flange coupling is efficient and is well known in the art, so will not be further described. A similar rectangular guide 17 is connected by similar choke and plain flanges 18 and 19 to the other end of the device.

30 Either of the two rectangular guides 11 and 17 can be used to introduce microwave energy to the device, the other guide then being the output, as the device is functionally bisymmetrical.

35 The rectangular guide 11 is connected through the flanges 12 and 13 and a short length of rectangular guide to a coaxial transmission line 21, a tuned side arm stub 22 being provided at the junction of the two types of transmission members to assist in matching or tuning out the impedance discontinuity caused by such a junction and for other reasons as will be further described.

40 It is necessary only that this side arm should support a waveguide mode for the microwave frequency which is to be employed, and therefore may be a short-circuited stub, which is closed at its upper end by a metallic plate.

45 The rectangular guide 17 is similarly connected to the other end of the same coaxial transmission line 21, employing a similar short-circuited rectangular side arm stub 23.

50 The coaxial transmission line 21 consists of a

central conductor 24 (Fig. 2) and an outer conductor 26. The left end (as illustrated in Fig. 2) of the outer conductor 26 is mechanically secured to the side arm matching stub 22 and through it to the flange 13. However, electrically the rectangular guide 11 secured to the flange 13 can be considered as being prolonged to the commencement of the coaxial transmission line at the juncture 27. Similarly, the right end of the outer conductor 26 is mechanically connected to the side arm stub 23 and through it to the flange 19.

The coaxial transmission line 21 should be so dimensioned that only the fundamental TEM mode will be propagated therethrough at the frequency impressed thereon. As is well known by those skilled in the art the limiting or cutoff wavelength in free space at which the first higher mode will be propagated is given approximately by the expression:

$$\lambda_c = \pi(a+b)$$

where a is the diameter of the inner conductor and b is the internal diameter of the outer conductor. Thus the dimensions a and b must be such that λ_c as calculated by the above expression is in excess of the wavelength in free space of the microwave energy impressed thereon. Likewise, the length of the coaxial line 21 lying between the rectangular wave guide inputs considered as the junction lines 27 and 28 should be at least a half wavelength in free space in length.

The center conductor 24 extends beyond the respective ends 27 and 28 of the coaxial transmission line into spaces which electrically are parts of the rectangular guides axially aligned with the coaxial transmission line. These extensions of the center conductor therefore constitute antennas extending axially into the guides. The extended antennas are tapered so that their ends 29 and 31 present relatively small areas to the rectangular guides and therefore produce only minor electrical discontinuities. However, non-tapered extensions could be used with minor changes in extension length to compensate for the impedance discontinuity introduced by the blunt ends.

The central conductor 24 is supported by two transverse rods 32 and 33 which extend from side to side of the rectangular guide and are secured in the narrower sides thereof. This is more clearly seen in Fig. 3. Since the two rods 32 and 33 are thin and are perpendicular at all points to the direction of the electric component of the field in the rectangular guide, these rods do not affect the impedance of the rectangular guide in which they are placed. The end 31 of the central conductor is not secured in any way.

The outer coaxial conductor 26, Fig. 2, is annularly broken at 34 to permit rotation, this break being made a point of low impedance by a closed folded slot one-half wavelength long. The one-half wavelength slot is folded into two quarter-wave cylindrical slots 36 and 37 and the mechanical junction 38 at the outer surface is a point of high impedance because it is one-quarter wavelength from the closed end of the slot. This design permits relative rotation of the two ends of the device without causing a discontinuity, sparking or radiation.

Numerous other designs of a wave-trap mechanical joint are known and may alternatively be used here. One such design, for example, consists simply of a coaxial transmission line

75 having a rotatable choke flange joint in its outer conductor.

In operation, microwave energy is applied to one end or the other of the device through the attached rectangular guide, for example through a guide attached to the flange 13. The electrical component of the field is thus vertical as it might be observed in Fig. 2, as the microwave energy is applied to the device. The energy flows into the side arm stub 22, the length of which is made to be an odd integral multiple of a quarter wavelength in guide, so that standing waves are generated with a voltage maximum at the horizontal axial plane of the incoming rectangular guide.

This is more easily visualized in Fig. 4, in which the electric component of the incoming energy is represented in the guide 11 by equally-spaced vertical lines 39. These lines bend around the corner 41, as indicated by the oblique line 42.

The line 43 represents the center line of the axially-placed antenna, and the closed end 44 of the side arm stub 22 being, for example, one-quarter wavelength from the antenna, a standing voltage loop is placed at the position of the antenna 43 with the direction of the concentrated electrical field along the direction of the antenna. This is the most favorable condition for coupling of the electrical field to the antenna, with the result that there is maximum coupling of the incoming field energy to the antenna 43, and the latter may therefore receive and extract substantially all of the energy from the incoming microwave field.

Viewed from the input rectangular guide 11, the presence of the side arm 22 and of the antenna both cause electrical discontinuities. However, their effects are completely matched out by proper design of the length L of the side arm and the distance D by which the antenna 43 extends into the rectangular guide space. Such dimensions are customarily determined empirically in microwave transmission apparatus, only rough and inaccurate calculations being possible in most cases. As an example, however, it has been found that where microwave energy having a frequency of 8800 megacycles is used, the length L may be 0.6 inch and the distance D 0.5 inch, when the coaxial line inner conductor diameter is .187", and the outer conductor inside diameter is .437".

The antenna 43 is merely a prolongation of the center conductor of the coaxial transmission line, the taper of the antenna as illustrated in Fig. 2 being desirable to permit employment of the best thickness of coaxial center conductor while presenting only a small area of the antenna end to the incoming energy. The described excitation of the antenna is most favorable for setting up the TEM mode of field about the coaxial center conductor, and the input energy is therefore transferred completely to the coaxial transmission line. At the output end, the construction being similar to that at the input end, the energy in the TEM field of the coaxial line is reconverted to $TE_{1,0}$ field mode energy in the output rectangular guide by a process which is the reverse of that described.

Since the microwave energy in the coaxial portion of the device is in the circularly symmetrical TEM mode, no electrical change is produced by mechanical rotation of one end of the device in relation to the other end. As the central conductor 24 is secured to one end only of the device, it rotates as a whole with that end of the device and no joint is required in it.

What is claimed is:

1. A microwave rotatable joint comprising, a pair of hollow guides in axial alignment, a coaxial line containing a coaxial rotary joint, first transition means connecting one of said hollow guides to one end of said coaxial line in axial alignment therewith, said first transition means including a transverse hollow guide matching stub, and second transition means connecting the other of said hollow guides to the other end of said coaxial line in axial alignment therewith, said second transition means including a transverse hollow guide matching stub. 10

2. A microwave rotatable joint comprising, a pair of hollow guides in axial alignment, a coaxial line containing a coaxial rotary joint, first transition means axially connecting one of said hollow guides to one end of said coaxial line in axial alignment therewith, said first transition means including a transverse hollow guide tuning stub and an antenna constituting an extension of the inner conductor of said coaxial line, and second transition means axially connecting the other of said hollow guides to the other end of said coaxial line in axial alignment therewith, said second transition means including a transverse hollow guide tuning stub and an antenna constituting an extension of the inner conductor of said coaxial line. 20

3. A microwave rotatable joint comprising, a pair of hollow guides in axial alignment, a coaxial line containing a coaxial rotary joint, first transition means axially connecting one of said hollow guides to one end of said coaxial line in axial alignment therewith, said first transition means including a hollow guide tuning stub perpendicular to the axis of the first hollow guide and an antenna prolongation of the inner conductor of said coaxial line, and second transition means axially connecting the other of said hollow guides to the other end of said coaxial line in axial alignment therewith, said second transition means including a hollow guide tuning stub perpendicular to the axis of the second hollow guide and an antenna prolongation of the inner conductor of said coaxial line. 30

4. A microwave rotatable joint comprising, a pair of hollow guides positioned with their axes in a single axial line, a coaxial line containing a coaxial rotary joint, the axis of which lies in said axial line, first transition means connecting one of said hollow guides to one end of said coaxial line with the axis of said one hollow guide lying in said axial line, said first transition means including a hollow guide short-circuited tuning stub having a length substantially equal to an odd integral multiple of a selected quarter microwave length and an antenna formed by a prolongation of one end of the inner conductor of said coaxial line, and second transition means connecting the other of said hollow guides to the other end of said coaxial line with the axis of said other hollow guide in said axial line, said second transition means including a hollow guide short-circuited tuning stub having a length substantially equal to an odd integral multiple of said selected quarter microwave length and an antenna formed by a 40

antenna formed by a prolongation of the other end of said inner conductor of the coaxial line. 5

5. A microwave rotatable joint comprising, a pair of hollow guides positioned with their axes in a single axial line, a coaxial line containing a coaxial rotary joint and having its axis lying in said axial line, a first transition connected between one of said hollow guides and one end of said coaxial line, said first transition including a hollow guide short-circuited tuning stub having a length substantially equal to an odd integral multiple of a selected quarter-microwave length, said stub being perpendicular to said axial line, and including a first antenna prolongation of one end of the inner conductor of said coaxial line, and a second transition connected between the other of said hollow guides and the other end of said coaxial line, said second transition including a hollow guide short-circuited tuning stub having a length substantially equal to an odd integral multiple of said selected quarter-microwave length, said stub being perpendicular to said axial line, and including a second antenna prolongation of the other end of the inner conductor of said coaxial line. 20

6. A microwave device in accordance with claim 5 in which said hollow guides are rectangular in cross section.

7. A microwave device in accordance with claim 6 in which said inner conductor is anchored by at least one transverse pin embedded at its ends in the narrow side walls of one of said rectangular hollow guides, said pin being perpendicular to said narrow side walls. 35

8. A microwave device in accordance with claim 5 in which said coaxial rotary joint is in the outer conductor only of said coaxial line and in which the inner conductor of said coaxial line is anchored at one end only. 40

9. A microwave transition for the in-line connection of a hollow guide to a coaxial line comprising, a tuned rectangular guide stub connected between the end of the hollow guide and the end of the coaxial line positioned with its axis perpendicular to the hollow guide, and an antenna positioned in said guide stub coaxially with and connected to the inner conductor of said coaxial line. 45

10. A microwave transition in accordance with claim 9 in which said guide stub is provided with a short circuit end portion and has a length equal to an odd integral multiple of one quarter of the wavelength of the microwave energy selected for energization. 50
